UNITED STATES PATENT OFFICE

2,182,287

MUSIC HOLDER

George M. Eads, Clarkston, Wash.

Application July 1, 1938, Serial No. 217,043

2 Claims. (Cl. 45—58)

This invention relates to improvements in music holders and has particular reference to a device for holding sheet music books and the like upon an accordion, so that the player of the accordion 5 may read the notes while moving about.

A further object is to produce a device of this character which is adjustable to accordions of various sizes.

A further object is to produce a device which 10 is economical to manufacture, neat in appearance, and easy to apply to the accordion.

Other objects and advantages will be apparent during the course of the following description.

In the accompanying drawing forming a part 15 of this specification and in which like numerals are employed to designate like parts throughout the same,

Fig. 1 is a top plan view of my device;

Fig. 2 is a side elevation of Fig. 1, showing a 20 portion of the accordion in dotted lines; and

Fig. 3 is a fragmentary bottom plan view of the extension arm of the device.

The average accordion player must memorize his notes for the reason that the player often 25 walks about and cannot stand in front of a music rack. I have, therefore, devised a music rack which may be attached to the accordion so that the player may walk about and yet clearly see the notes.

30 In the accompanying drawing wherein for the purpose of illustration is shown a preferred embodiment of my invention, the dotted lines in Figs. 1 and 2 designate a portion of an accordion; and upon the top of this accordion there is a 35 strap holder, shown in dotted lines at 5. This strap holder forms means by which the shoulder straps and body straps of the accordion may be attached. It is my intention to employ this strap holder to attach my device to the accordion. At

40 6 and 7 I have shown a pair of spring arms which are secured to an offset member 8, slidably engaging a tubular member 9, which in turn slidably engages a support 11, secured to the top of the accordion through the medium of a suction cup 12. A bar 13 is pivoted to the support 11 and extends down the end of the accordion and carries a sliding U-shaped clamp 14. An extension arm 16 is pivoted as at 17 to the U-shaped clamp, and a thumb nut 18 serves the 45 purpose of securing the U-shaped clamp in adjusted positions along the bar 13 and also to hold the extension arm 16 in any desired angular position, as indicated in the full and dotted lines of Fig. 2. This extension arm has a cross piece 50 19 secured thereto and a pair of lazy tongs 21,

which are provided with clamps 23 and 24 respectively. The use of the lazy tongs is well-known; therefore, further reference thereto is unnecessary. It will be further understood that the lazy tongs, clamps and piece 19 provide a 5 support and holding means for a book or sheets of music.

Cooperating with the clamps 23 and 24, to hold the pages of a book or the music, against 10 casual removal from the support provided by the lazy tongs, I provide a rod 26 having a finger piece 27, which rod bends over the end of the extension arm 16, as shown at A in Fig. 1, and has a flat plate 28 secured thereto. This flat plate is adapted to overlie the portion of the pages 15 adjacent the fold thereof, as will be obvious. When the rod is pushed to the dotted line position of Fig. 3, this plate 28 will lie beyond the outer margin of the pages, after which the pages 20 may be turned, and then the plate is reengaged with the pages.

It is to be understood that the form of my invention herewith shown and described is to be taken as a preferred example of the same and that various changes relative to the material, 25 size, shape and arrangement of parts may be resorted to without departing from the spirit of the invention or the scope of the subjoined claims.

Having thus described my invention, I claim:

1. An accordion music holder of the class described including an expandable gripping member adapted to engage the handle of the accordion, an offset bar secured to said gripping member, a supporting element adjustably secured to said offset bar, a second bar pivotally secured to said support, a pivoted music holder slidable upon said bar, and lazy tong elements carried by said music holder and having clamps capable of gripping the music sheet edges. 30

2. An accordion music holder of the class described including an expandable gripping member adapted to engage the handle of the accordion, an offset bar secured to said gripping member, a supporting element adjustably secured to said offset bar, a second depending bar pivotally secured to said support, a pivoted music holder slidable upon said depending bar, said music holder including an extension arm having lazy tong elements arranged on opposite sides thereof 45 and including music clamp members, and an additional slidable clamp plate mounted upon said extension arm to grip the central sections 50 of the music sheets.
